DESIGN FOR A WALLPAPER

Emile Ericson, New York, N. Y.

Application September 17, 1940, Serial No. 95,130

Term of patent 3½ years

To all whom it may concern:

Be it known that I, Emile Ericson, a citizen of the United States of America, residing in New York, county of New York, and State of New York, have invented a new, original, and ornamental Design for a Wallpaper, of which the following is a specification, reference being had to the accompanying drawing, forming part thereof, wherein the figure of the drawing is a plan view of a wallpaper showing my design.

I claim:

The ornamental design for a wallpaper, substantially as shown.

EMILE ERICSON.
